AUTOMATICALLY ACTUATED WEATHER STRIP

Filed Nov. 1, 1929

UNITED STATES PATENT OFFICE

EDGAR J. CHANDLER, OF OAKLAND, CALIFORNIA, ASSIGNOR OF ONE-HALF TO HAROLD M. STEVES, OF OAKLAND, CALIFORNIA

AUTOMATICALLY ACTUATED WEATHER STRIP

Application filed November 1, 1929. Serial No. 404,009.

The present invention relates, broadly, to improvements in weather-strips for doors and like swinging closures, but more particularly to improvements in automatically actuated weather-strips wherein the strip is automatically retracted into a recess in the bottom edge of the closure when swung open and is dropped to operative position when the closure is in closed position.

10 The device in the present invention is of a simple and efficient character and embodies a hinged strip of metal having a rubber strip secured therein, which rubber strip is pressed against the floor when the door, or other closure, is in closed position, and is raised clear of the floor when the closure is opened, the means for actuating the same being wholly automatic and operated through the swinging action of the closure.

20 The primary object of the invention is to provide an automatically operated weather-strip for doors and like closures that is simple in construction and positive in its action.

Another object of the invention is to provide an automatically operated weather-strip of the class indicated that will automatically swing clear of the floor when the closure is opened and that will be automatically urged to operative position when the closure is 30 closed.

Another object of the invention is the provision of novel means for the automatic actuation of the weather-strip to both retracted and operative positions.

35 Other objects and advantages of the invention will become apparent with reference to the subjoined specification and the accompanying one sheet of drawings in which:—

40 Figure 1 is an elevation of a door, shown equipped with the improved automatically operated weather-strip;

45 Figure 2 is an enlarged plan section of a door casing and door, a portion of which is broken away, illustrating the weather-strip in position and showing the means for actuating the same, the section being indicated by the line 2—2, in Figure 1;

50 Figure 3 is an enlarged sectional detail illustrating the strip as it appears in operative

position, the section being indicated by the line 3—3, in Figure 2;

55 Figure 4 is a perspective view of the strip per se, showing the retracting spring and the actuating arm thereof;

Figure 5 is a perspective view of one end of the strip, showing the means and method of hinging the same to the lower edge of the closure; and

60 Figure 6 is a perspective view of the re-tracting spring per se.

Referring more particularly to the drawings, in which the preferred embodiment of the invention has been shown, the numeral 10 designates a hinged closure, such as a door, 65 hinged to the frame 11 by the usual hinges 12.

The lower edge of the closure is grooved, as indicated at 13, providing a tongue 14 on its inner edge extending the full width of the closure, as clearly indicated in Figure 3. The 70 weather-strip 15 is positioned in this groove and has its rear edge 16 abutting against the tongue 14 when in position on the closure.

75 The weather-strip per se comprises a strip of metal, preferably galvanized iron, bent upon itself and forming upper and lower gripping members 17 and 18 between the free edges of which is inserted a rubber strip 19, said strip 19 being securely held in place by the clamping action of the members 17 and 80 18, which are pressed tightly together in any suitable manner after the rubber strip has been inserted in place.

85 One end edge of one of the members 18 of the strip is bent up and over the other, as indicated at 20 in Figure 5, while the opposite end of both sections 17 and 18 are bent up at right angles to the body of the strip at the opposite end thereof to form an actuating arm 21, Figures 2, 4 and 5.

90 Spring means 22 is provided for normally retracting the strip and embodies an elongated section of steel wire having at one end an upstanding section 23 and at the other end a hook section 24. This spring, as thus formed, is inserted through a slot 25 formed in the section 17 of the strip with the upstanding section 23 projecting upwardly therefrom, as indicated in Figures 3, 4, 95 and 5.

100

The hook section 24 of the spring lies flatwise between the sections 17 and 18 of the strip and when said strip is in place the upstanding section 23 thereof projects into a hole 26, Figure 3, provided in the closure for its reception.

In attaching the strip to the closure a plurality of openings 27 are provided in the inner edge 16 thereof and a plurality of 10 staples 28 are inserted through these openings and driven home into the inner edge of the closure, as indicated in Figure 3, these staples forming hinge members providing for free swinging movement of the strip relative to 15 the closure.

The spring 22 having a torsional urge tends to normally hold the strip retracted in the groove 13 of the closure and substantially flush with the lower edge of the tongue 14 20 thereof.

The arm 21 of the strip, when in place upon the closure, lies flat against the lower free corner thereof, as indicated in Figure 2, with this arm projecting into the path of a 25 stop 29 positioned on the inner side of the casing member 30, so as to engage the arm 21 of the strip when the door is in closed position and force the same to the position shown in Figure 3, or in operative position, with the 30 rubber strip 19 engaging the floor.

When the closure is opened the arm 21 leaves the stop 29 and the strip is instantaneously forced to inoperative position in the groove 13 by the torsional urge of spring 35 22.

When the strip is in operative position, as in Figure 3, the rubber strip 19, being resilient, presses downwardly against the floor and tightly seals the opening between the 40 lower edge of the closure and the floor, thus preventing the entrance of undesirable drafts through this channel.

The strip, of course, may be applied to various closures, such as swinging windows and 45 the like, and will serve to prevent drafts from this source equally as well.

Having thus described my invention I claim and desire to secure by Letters Patent of the United States, the following:

50 1. A weather-strip adapted to be hingedly secured to a swinging closure between one edge thereof and its frame, said strip comprising a metal strip bent upon itself to form a clamp, one of the members of the clamp 55 having an end portion bent to overlap the other member of the clamp, an upwardly extending integral arm on one end of said clamp, a spring rod carried by the clamp, said rod having an arm extending upwardly from 60 the clamp and mounted in a recess in the closure, said rod having a flat hooked end fitted in the bend in the clamp.

2. A weather-strip adapted to be hingedly secured to a swinging closure between one 65 edge thereof and its frame, said strip com-

prising a metal strip bent upon itself to form a clamp, one of the members of the clamp having an end portion bent to overlap the other member of the clamp, means for moving the strip to inoperative position, said means comprising a spring rod fitted in the bend of the clamp, said rod having an arm extending upwardly from the clamp and mounted in a recess in the closure, said rod having a flat hooked end fitted in the bend 70 in the closure.

In testimony whereof, I hereunto affix my signature.

EDGAR J. CHANDLER.
